UNITED STATES PATENT OFFICE

125,638

DESIGN FOR A GLASS BOTTLE

Lawrence J. Kihn, Pittsburgh, Pa., assignor to
J. T. & A. Hamilton Company, a corporation of Pennsylvania

Application January 8, 1941, Serial No. 97,895

Term of patent 7 years

To whom it may concern:

Be it known that I, Lawrence J. Kihn, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

Fig. I is a front elevational view of a glass bottle showing my new design.

Fig. II is a top plan view thereof.

The back of the bottle is identical with the front.

I claim:

The ornamental design for a glass bottle, substantially as shown and described.

LAWRENCE J. KIHN.
